PORTABLE CORDLESS DRILL

Thomas C. Butler and Samuel H. Kohler, Baltimore, Md.,
assignors to The Black and Decker Manufacturing Com-
pany, Towson, Md., a corporation of Maryland

Filed Apr. 13, 1961, Ser. No. 64,727

Term of patent 14 years

(Cl. D54—14)

FIG. 1

Des. 193,025

PAGE 2

FIG. 2

Des. 193,025

PAGE 3

FIG. 4

FIG. 5

FIGURE 1 is a front perspective view of a portable cordless drill, showing my new design;

FIGURE 2 is a rear perspective view as viewed from the opposite side of the drill;

FIGURE 3 is a side elevational view;

FIGURE 4 is a front elevational view with the drill chuck omitted for convenience of illustration; and

FIGURE 5 is a rear elevational view.

The dominant features of my design reside in the portions shown in full lines.

We claim:

The ornamental design for a portable cordless drill, as shown and described.
